CLAIM

The ornamental design for a combined vehicle front bumper and guard, as shown and described.

DESCRIPTION

FIG. 1 is a front perspective view showing my new design for a combined vehicle front bumper and guard;

FIG. 2 is a rear elevational view thereof;

FIG. 3 is a top plan view thereof;

FIG. 4 is a bottom plan view thereof; and

FIG. 5 is an end elevational view thereof;

The end opposite that shown in FIG. 5 is the mirror image thereof.

The broken lines in FIG. 1 are for illustrative purposes only and form no part of the claimed design.

FIG. 1

FIG. 2
